BOILER TUBE CLEANER

Filed March 8, 1930

DAVID W. GROVES Inventor

By *Herbert E. Smith*

Attorney

UNITED STATES PATENT OFFICE

DAVID W. GROVES, OF COEUR D'ALENE, IDAHO

BOILER TUBE CLEANER

Application filed March 8, 1930. Serial No. 434,264.

My present invention relates to improvements in boiler tube cleaners and the invention is embodied in bearing head of the fixture or attachment by means of which the 5 cleaner is conveniently located and supported in the front space or combustion chamber of the horizontal return tubular type of boiler.

In carrying out my invention I utilize steam pressure, and provide rotary means, 10 preferably under manual control and operation, for distributing jets of steam from the nozzles and directing the steam jets into the boiler tubes for cleansing them of soot and other accumulations.

15 By the utilization of the tube cleaner all of the boiler tubes may quickly and thoroughly be cleansed, at a comparatively slight cost, and without material loss of time in the suspension of boiler operations. The 20 cleaning device forms an attachment having a journal bearing or bearing head adjacent the front ends of the boiler tubes, and which may be installed with facility, and conveniently manipulated at required intervals 25 for maintaining the boiler in most efficient operative condition.

The invention consists in certain novel combinations and arrangement of parts in the bearing head of the tube cleaner as will hereinafter be more fully set forth and claimed.

30 In the accompanying drawing I have illustrated one complete example of the physical embodiment of my invention, wherein the parts are combined and arranged according to one mode I have thus far devised for the practical application of the principles of my invention.

Figure 1 is a view at the front of a boiler, 35 with its doors open, and disclosing the installation of the tube cleaner of my invention.

Figure 2 is a horizontal sectional view at line 2—2 of Figure 1.

40 Figure 3 is an enlarged, detail sectional view showing the journal bearing for the steam distributing pipe, the steam ports, and crank handle.

45 Figure 4 is an edge view of one of the steam nozzles, and Figure 5 is a side view of one of the steam nozzles.

In order that the general arrangement and relation of parts may readily be understood I have shown in Figures 1 and 2 part of a boiler of the horizontal return tubular type, the boiler being indicated by the numeral 1 and the tubes as 2. The usual side walls 3 and combustion chamber or front space 4 of the boiler are illustrated, and the front doors 5 and 6 are hinged as usual at 7 for enclosing the combustion chamber or front space.

55 In equipping the boiler with the device of my invention I preferably use a pair of notches 8, which together form a central opening in the doors 5 and 6 when the latter are closed, and which opening is utilized in the operation of the device.

60 A cross beam 9, of metal, is built into the side walls of the furnace and located in horizontal position just below the axial line of the boiler for supporting the cleaner.

65 A hollow bearing head 10 is attached by its flanges 11 and bolts 12 on the upper side of the cross beam 9 for supporting the rotary part of the cleaner, and a live steam pipe 13, 70 from a suitable source of supply is connected at 14 to furnish steam to the bearing head.

75 When the cleaner is to be utilized, a cut off valve 15, in the steam pipe, exterior of the furnace, is opened to admit steam to the hollow bearing head, and from the head the steam is distributed through a distributing pipe 16. This pipe is fashioned with a tapered, angular, journal 17 which is rotatable in the bearing head and fashioned with steam 80 ports or longitudinal slots 18 for passage of the steam from the head to the interior of the distributing pipe while the latter is revolving on its journal.

85 At its outer end the journal is provided with a closed head 19 and the head is fashioned with a threaded boss 20 and shank 21 projecting from the bearing head 10. A washer 20a and a nut 22 on the threaded boss 90 are used to close the smaller end of the tapered bearing head, and the larger end of this bearing head is closed by its engagement with the tapered journal of the distributing pipe, the journal and shank 21 of course being revolvable with the distributing arm 16 95 100

as it swings in a vertical plane on front of the tubes.

A crank handle 23 is attached on the squared end of the shank, after the doors 5 and 6 are closed, and the distributing pipe is 5 swung in a circle and in a vertical plane in the combustion chamber or front space of the boiler as the crank handle is turned by hand outside of the doors.

10 As seen in Figure 1 the distributing pipe may be fashioned along the lines of a compound curve and it is of sufficient length to the circumferential periphery of the boiler. Along the inner side of the pipe are arranged 15 a row of nozzles 24 which are threaded in the wall of the pipe by means of bosses 25. The nozzles as shown in Figures 4 and 5 are flat and are tapered, with their walls converging toward the mouth of the nozzle to increase 20 the velocity of the jet, of steam rushing from the nozzle and directed into the tubes.

The nozzles are arranged with their flat sides parallel with the axial line of the steam distributing pipe, and the nozzles are spaced 25 apart a distance less than the distance between centers of the boiler tubes, in order that, as the pipe swings around in its circular path, the nozzles will direct a jet of steam into all of the tubes of the boiler, and in this 30 manner the steam jets reach every part of the tubular structure for cleansing the tubes.

Having thus fully described my invention, what I claim as new and desire to secure by Letters Patent is:—

35 In a bearing head for a boiler cleaner, the combination with an open-end, tapered head and a steam supply pipe connected thereto, of a ported, tapered, hollow journal supported in said head and provided with a rear 40 closed end, a threaded boss on said end, a washer on the boss closing the rear end of the hollow head, a lock nut on the boss, and means united with the threaded boss for turning the hollow journal.

45 In testimony whereof I affix my signature.
DAVID W. GROVES.
